UNITED STATES PATENT OFFICE.

WILLIAM GRAY AND EDWARD E. TAYLOR, OF AMESBURY, MASSACHUSETTS.

DESIGN FOR AN AUTOMOBILE-LAMP.

41,542.

Specification for Design.

Patented July 4, 1911.

Continuation of application Serial No. 508,248, filed July 17, 1909. This application filed April 17, 1911.
Serial No. 621,631. Term of patent 7 years.

To all whom it may concern:

Be it known that we, WILLIAM GRAY and EDWARD E. TAYLOR, citizens of the United States, residing at Amesbury, in the county of Essex and State of Massachusetts, have invented a new, original, and ornamental Design for Automobile-Lamps, for which on July 17, 1909, we made application for Design Letters Patent, Serial No. 508,248, the present application being a continuation of the same, and of which the following is a specification, reference being had to the accompanying drawings, forming part thereof.

Figure 1 is a view in perspective of an automobile lamp showing our design. Fig. 2 is a view in perspective of the lamp as it appears when viewed from the side directly opposite that shown by Fig. 1.

We claim:

The ornamental design for an automobile lamp, as shown.

WILLIAM GRAY.

EDWARD E. TAYLOR.
